UNITED STATES PATENT OFFICE.

REGINALD WILLIAM PENN, OF BLACKHEATH, AND WILLIAM ALFRED STEPHENS, OF SHEPHERDS BUSH, LONDON, ENGLAND.

CLOSURE FOR BOTTLES AND OTHER RECEPTACLES.

Application filed September 2, 1925, Serial No. 54,028, and in Great Britain September 5, 1924.

This invention relates to closures for bottles and other receptacles.

A closure embodying this invention comprises an elastically deformable cap having a depending rim and pressure members on, in, or associated with, the upper surface adjacent the edge to establish sealing relation between the cap and the receptacle, and locking members on the rim of the cap for co-

10 acting with the receptacle, said pressure members being adapted to cause the rim to be distorted inwardly at or about the locking members, and outwardly at or about points remote from the locking members 15 when the cap is pressed over the receptacle to close it, whereby, when pressure is applied to the rim at the outwardly distorted points, the locking members are released.

20 The closure is adapted to be applied to a receptacle neck which has an external projecting tapered or bevelled rim (which, although preferably continuous, may be discontinuous) just below its opening, with which rim the cap is adapted to engage at 25 oppositely disposed places when the rim of the cap is distorted inwardly as above set forth.

30 The closure may be applied with or without a sealing washer or disc, but when a washer or disc is used it must be of sufficient thickness and elasticity to compensate for the variation in pressure between the different parts of the pressure members, which pressure will, under practical conditions, be 35 non-uniform.

Reference will now be made to the accompanying drawings which show, as examples, several forms of closure made in accordance with this invention, and of which:

40 Fig. 1 shows one form of cap in underside plan;

Fig. 2 shows a cross-section of the same cap in position on the neck of a receptacle, on the line X—X of Fig. 1; and

45 Fig. 3 shows the same in section on the line Y—Y of Fig. 1;

Fig. 4 shows a sectional elevation of an alternative form of cap; and

50 Fig. 5 shows diagrammatically the formation of the sealing disc or washer embodied in the cap represented in Fig. 4;

Fig. 6 shows, in plan, the top of a cap of another form;

Fig. 7 shows the underside of same in plan;

Fig. 8 shows an elevation of the cap;

Fig. 9 shows a sectional elevation of the cap on the line W—W of Fig. 7; and

Fig. 10 shows the same on the line Z—Z of Fig. 7; and,

Fig. 11 shows a further form of cap in underside plan.

The same letters of reference are used throughout to designate the same or corresponding parts.

Referring to Figs. 1, 2 and 3, the cap *a* is provided near its edge with two grooves or channels *b*, *b*, the depths of the said grooves or channels being greatest at two places *c*, *c* which are diametrically opposite, and least at the two places *d*, *d* most remote from these; where the depth is least, the grooves or channels merge into or nearly into the surface of the top of the cap *a*. Thus, in the latter case, the grooves or channels *b*, *b* compose one groove or channel. Therefore, the grooves or channels *b*, *b* with their parts *c*, *c* and *d*, *d* produce continuous or discontinuous protuberances of varying depth which constitute the aforesaid pressure members.

The cap *a* has its edge turned down to form a continuous rim *e*, and the lower edge *f* of this rim *e* is turned in to engage with a projecting rim *h* on the neck *g* of the receptacle.

A packing or sealing disc or washer *j* is provided between the cap *a* and the top of the receptacle to ensure a tight joint.

When the cap *a* is applied to the neck *g* of the receptacle pressure is applied to the parts *d*, *d* of the cap *a* where the grooves or channels *b*, *b* are shallowest and the cap *a* is thereby caused to become arched. The rim *e* is thus made to become oval and bulges inwardly at *d*, *d* below the points where the pressure is applied, engaging with the rim *h*, and bulges outwardly at the intermediate points *c*, *c*.

Squeezing the rim *e* where it is bulged outwardly, i. e., at *c*, *c* counteracts its distortion and enables the cap to be removed.

Referring now to Figs. 4 and 5, which represent another form of closure or cap *a* embodying this invention, the grooves or channels *b*, *b* are dispensed with by making

the sealing washer or disc *k* of varying thickness, by making it, for instance, flat on one face and giving its other face a slight cylindrical curvature. Other forms of disc 5 *k* may be substituted for this, provided that they serve to impart the necessary curvature to the cap *a*. In this construction it may be advisable to cement the disc *k* to the cap *a* and to mark the latter to ensure proper 10 positioning.

The appearance and efficiency of the cap *a* may be improved by giving a slight curvature to its lowermost edge as shown at *m* in Fig. 4.

15 In the constructions set out above, the inner diameter of the inturned lower edge *f* of the cap *a* will, in general, be such as will just clear the rim *h* on the neck *g* of the receptacle. No engagement will, therefore, 20 take place until the cap *a* has been forced down by applying pressure to the appropriate points as set out above. In an alternative construction, which is illustrated in Figs. 6, 7, 8, 9 and 10, to meet variations in 25 the manufacture of the receptacles and closures and give a more efficient lock and retaining means, the inturned rim *f* and part of the downturned rim *e* are indented in two or several places to form locking members 30 *n*, *n*, preferably four as represented, and the inner points or edges of the indentations *n*, *n* lie on a circle of smaller diameter than that of the rim *h* on the receptacle.

The four indentations *n*, *n* are best located 35 in two close pairs, one indentation *n* being placed on each side of, and close to, the points *d*, *d* where the grooves or channels *b*, *b* are shallowest, or the corresponding points where a disc or washer *k* of of non-uniform 40 thickness is used. The non-indented part of the rim *e* is large enough to clear the rim *h* of the receptacle, and two opposite pairs of clearances are thus provided, one permitting the inward bulging of the rim *e* at *d*, 45 *d* to permit of distortion and engagement, the other permitting the rim *e* of the cap *a* to be distorted by squeezing at *c*, *c* for the purpose of removing the cap. Thus the indentations *n*, *n* are in spaced relation with 50 the deepest parts *c*, *c* of the grooves or channels *b*, *b*.

The joint action of the parts *c*, *c* and *d*, *d* and of the indentations *n*, *n* will be understood from the following which exemplifies 55 one method of applying the cap.

The cap *a* is placed over the top of the receptacle with the indentations *n*, *n*, at the one side below the rim *h* of the receptacle, and, in consequence, it lies on an incline, 60 with the indentations *n*, *n* at the other side reposing on the top of the rim *h*. Now, on applying pressure to the cap anywhere, but, preferably, where it is highest, i. e., over the indentations *n*, *n* above the rim *h*, the two 65 parts *c*, *c* receive and take the greatest pres-

sure, and on pressing these indentations over the rim *h* the pressure is absorbed by the whole of the grooves or channels *b*, *b*, although, in the fully-closed position, there is always greater pressure at the parts *c*, *c* than 70 at the parts *d*, *d*.

To remove the cap *a*, pressure is applied to the rim laterally and adjacent the parts *c*, *c* of the grooves or channels *b*, *b* where sufficient clearance is provided to allow 75 movement, thereby causing the indentations *n*, *n* on one side or both to disengage,

In the closures illustrated in Figs. 1, 2 and 3, and in Figs. 6, 7, 8, 9 and 10, the grooves or channels *b*, *b* with their parts *c* and *d* constituting the pressure members or protuberances are shown discontinuous and practically continuous, respectively, and of varying depth, and, although this is desirable, it is not absolutely necessary as is represented in Fig. 11 where the pressure members are depicted as short or discontinuous protuberances extending partially around the lid *a*, and which may be of constant or varying depth. 85 90

We have described with reference to, and illustrated in, Figs. 1, 2 and 3, Figs. 6, 7, 8, 9 and 10, and Fig. 11, the provision of the pressure members *b*, *c*, *d* integral with the cap *a*, and although we prefer this construction, such members may be provided on a disc of tin or any other suitable material adapted to be slipped, and appropriately positioned, within the cap *a* thus adopting the idea included in Figs. 4 and 5 with regard to the disc or washer *k* in which event the top of the cap *a* may be closed as represented, or open in the form of an annulus or otherwise. 95 100

We have described and illustrated the closure as cylindrical, but, of course, it may be of any shape to conform to the contour of the receptacle, i. e., for example, it may be oval, rectangular or polygonal, consequently, when we, for instance, refer to diameter and so forth, it will be understood the consequential variation in terms is included. 110

In such cases, obviously, the pressure members and the locking members may be arranged in sundry ways. For example, in a receptacle of triangular cross-section, the grooves *b*, *b* may follow the sides, with a part *c* disposed centrally of each side and a part *d* provided at each angle, whilst a locking member *n* may likewise be located at each angle. 115 120

From the foregoing, it will be evident that in a closure made in accordance with this invention, whatever the construction adopted, the internal surface of the lid *a* is never a complete surface of rotation. 125

What we claim and desire to secure by Letters Patent is:

1. A closure for receptacles comprising a cap having a continuous rim for engaging 130

and disengaging the neck of the receptacle, and pressure members of variable depth associated with the top of said cap for co-acting with the corresponding part of said neck, 5 said pressure members following the contour of said rim in inward spaced relation thereto.

2. A closure for receptacles comprising a cap having a continuous rim for engaging 10 and disengaging the neck of said receptacle, and pressure members of variable depth associated with the top of said cap for co-acting with the corresponding part of said neck, said pressure members being spacedly positioned 15 relatively to said rim and following the contour thereof, the parts of said pressure members of least depth being situated in opposing relation, and the parts of greatest depth likewise being in opposing relation 20 transversely of the said opposing parts of the least depth.

3. A closure for receptacles comprising a cap having a continuous rim for engaging and disengaging the neck of the receptacle, 25 pressure members of variable depth associated with the top of said cap for co-acting with the corresponding part of said neck, said pressure members following the contour of said rim in inward spaced relation 30 thereto, and locking members on said rim for co-operating with the neck of the receptacle, said locking members being distantly located relatively to the deepest portions of said 35 pressure members.

4. A closure for receptacles comprising a cap having a continuous rim for engaging and disengaging the neck of the receptacle, pressure members of variable depth associated with the top of said cap for co- 40 acting with the corresponding part of said neck, said pressure members being spacedly positioned relatively to said rim and following the contour thereof, the parts of said pressure members of least depth being situated 45 in opposing relation and the parts of greatest depth likewise being in opposing relation transversely of said opposing parts of the least depth, and locking members on said rim for co-operating with the neck of 50 the receptacle, said locking members being positioned in close contiguity to the shallowest portions of said pressure members.

5. A closure for receptacles comprising a cap, a rim to the cap, locking members pro-

vided on portions of the rim and adapted to 55 engage a rim on the receptacle, said locking members being substantially diametrically disposed, a packing between the receptacle and the cap, a groove of varying depth on the upper surface and near the edge of the 60 cap forming at least one embossment of varying depth on the under surface adapted to bear on the packing, said embossment being deepest at the points most remote from the locking members. 65

6. A closure for receptacles comprising a cap, a rim to the cap, locking members provided on portions of the rim and adapted to engage a rim on the receptacle, said locking members being substantially diametrically disposed, a packing between the receptacle and the cap, a groove of varying depth on the upper surface and near the edge of the cap forming at least one embossment of 70 varying depth on the under surface adapted to bear on the packing, said embossment being deepest at the points most remote from the locking members and causing the rim to be distorted inwardly in the region of the locking members and outwardly in the region of the points remote from them when the cap is placed in position over the receptacle to close it, whereby, when pressure is applied to the rim at the outwardly distorted points, said locking members are 75 released. 80

7. A closure for receptacles comprising a cap, a rim to the cap, locking members provided on portions of the rim and adapted to engage a rim on the receptacle, said locking 90 members being substantially diametrically disposed, a packing between the bottle and the cap, a groove of varying depth on the upper surface and near the edge of the cap forming at least one embossment of varying 95 depth on the under surface adapted to bear on the packing, said embossment being deepest at the points most remote from the locking members which are located in close pairs in the form of indentations, one indentation 100 being placed on each side of, and close to, the points where the embossment is shallowest.

In testimony whereof, we affix our signatures.

REGINALD WILLIAM PENN.
WILLIAM ALFRED STEPHENS.
